UNITED STATES PATENT OFFICE.

OLIVER C. GRINNELL, JR., OF BROOKLYN, NEW YORK.

DESIGN FOR A CLOTH FABRIC.

No. 38,438.

Specification for Design.

Patented Jan. 29, 1907.

Application filed December 11, 1906. Serial No. 347,368. Term of patent 7 years.

To all whom it may concern:

Be it known that I, OLIVER C. GRINNELL, Jr., residing at Brooklyn, in the county of Kings and State of New York, have invented a new, original, and ornamental Design for Cloth Fabric, of which the following is a specification, reference being had to the accompanying drawing, forming part thereof.

The figure is a plan view of a sheet of cloth, showing my new design.

I claim—

The ornamental design for cloth fabric, as shown.

OLIVER C. GRINNELL, JR.
